UNITED STATES PATENT OFFICE.

HAROLD F. SHEPHERD, OF TOLEDO, OHIO, ASSIGNOR TO THE KENT-OWENS MACHINE COMPANY, OF TOLEDO, OHIO, A CORPORATION OF OHIO.

METHOD OF AND APPARATUS FOR DELIVERING MEASURED CHARGES.

Application filed June 15, 1925. Serial No. 37,400.

This invention is designed particularly for delivering measured charges of fuel to oil burning engines. These charges are comparatively very small but in order to affect a proper control and operation of the engine for the various loads it is desirable that the measuring be very accurately done not only as to the total quantity of fuel but where there are a number of cylinders as 10 to the amount fed to each cylinder.

In carrying out my invention I utilize a pulsating forcing pump in connection with a measuring device comprising a pump and deliver fuel to the forcing pump during the 15 forcing stroke of the forcing pump and thus more accurately and definitely cut off the measuring charge which is delivered to the forcing pump in each operation. Features and details of the invention will appear from 20 the specification and claims.

The invention is illustrated in the accompanying drawings which show an apparatus for carrying out the method as follows:—

Fig. 1 is a central vertical section through 25 an engine with the controlling apparatus thereon.

Fig. 2 an end elevation, parts being in section to better show construction.

Fig. 3 an illustrative diagram of the apparatus.

1 marks the frame of the engine, 2 the crank case, 4 the cylinders, 5 water jackets for the cylinders formed in the frame, 6 pistons operating the cylinders, 7 connecting rods, 8 cranks, 9 a crank shaft in which the cranks are formed, 10 crank shaft bearings, 11 spray nozzles, 12 pipes leading to the spray nozzles, 13 a forcing pump, one for each cylinder, forcing the fuel to the spray 40 nozzles, 14 a gear driving the force pumps through a shaft 14^a, 15 a gear with which the gear 14 meshes, the gear 15 being mounted on the crank shaft, 16 delivery pipes delivering fuel to the forcing pumps, 45 17 a pipe discharging to the pipes 16, 18 a rotary pump forming part of the measuring device, and 19 a bypass valve leading from the pipe 17 and controlling the moment of delivery to the force pumps. The bypass valve is controlled by a governor 20 driven from a shaft 21. The shaft 21 is driven by a gear 22 meshing with the gear 14. A sleeve 23 is responsive to the governor action and delivers its movement to a

lever 24. The lever 24 is connected by a link 25 with devices actuating the bypass.

The pump 18 of the measuring device is preferably of the rotary type having an intake 26 and involves gears 18^a, one of which is mounted on the shaft 14^a. These gears are 60 mounted in a pump chamber 18^b.

The bypass valve 19 has a body 27 and a pipe 28 leading from the pipe 17 connects the pipe 17 with a chamber 29 of the valve. A valve head 30 operates on a seat 31 and 65 controls the bypass opening 31^a. A discharge pipe 32 leads from this opening to the common source of supply of fuel. A spring 33 operates on the stem 31^b of the bypass valve and tends to hold it in closed 70 position. A push rod 34 is arranged in the packing 35 and leads from the end of the stem 31^b to without the body 27 and is operated upon by a tappet 36 carried by a rock arm 37. The rock arm 37 is mounted on a 75 rock shaft 38, the rock shaft being carried by a hanger 39 on a sleeve 40, the purpose of the sleeve being hereinafter more fully described. A cam platen 41 is rotatably mounted in the rock arm and operates 80 against a cam 42, the cam having the raised portions 44 which are concentric and depressions 43. When the platen drops into the depressions 43, it permits the dropping of the rock arm and consequently the closing 85 of the bypass valve under the influence of the spring 33. When on the raised portion 44 the rock arm is thrown upwardly thus opening the bypass valve.

The force pump has a pump chamber 45 90 with a liner 46. A pump plunger 47 operates in the liner and is provided with a head 48. A spring 49 is arranged around the plunger under the head 48 and tends to retract the plunger. A guide head 50 operates 95 on the head 48 and this is engaged by a rolling block 51 carried by a rock arm 52. The rock arm 52 is mounted on a rock shaft 53 and carries a roller 54. The roller is operated upon by a cam 55 shown in dotted lines 100 in Fig. 2, the several cams being shown in outline in Fig. 3, all the cams being carried by the shaft 14^a. The pipe 16 delivers to an inlet chamber 56 and the passage 57 leads from this chamber to the pump chamber. An inlet valve 58 controls the passage 57 and a spring 59 operates on the stem 58^a of the inlet valve and tends to close the same. 105

The fuel is discharged from the force pump through the pipe 12 to the spray nozzle 11. This is provided with the usual valve 62 loaded by a spring 63.

5 The sleeve 40 is hung on a pin 64 which is carried by a trunnion 65 in bearings 66 on the frame. The pin 64 is eccentric to the trunnion and consequently slightly raises and lowers the sleeve 40 as the pin 64 is 10 swung. A lever arm 66^a is carried by the pin 64 and this is connected by the link 25 with the lever 24. The lever 24 is preferably formed with two arms, one of which is shown in Fig. 2 and these arms are mounted 15 on trunnions or pins 69 carried by the frame. The upper ends of the lever are pivotally connected by means of the pins 70 on the sleeve 23. The governor is of the usual centrifugal type having the centrifugal 20 weights 71 and the centripetally acting springs 72. The detail mechanism connecting the governor elements 70 and 71 with the sleeve responsive to their movement is not shown but any well-known mechanism of 25 this type may be used. When the speed increases the action of the weights throws the lever 24 and thus the pin 64 so as to lift the rock arm 37 and consequently increases the time during which the bypass valve 30 is 30 opened, or in other words, retards the time when the bypass closes and in this way decreases the interval during which it is closed, thus decreasing the supply of fuel in as much as fuel is delivered to the force pump 35 only during the period in which the bypass valve is closed.

In the schematic drawing the details can be readily followed from those of the general construction. The force pump plungers, 40 however, as shown are supplied with rollers 73 which operate directly on the cams 55.

45 Following the operation of the apparatus the measuring pump 18 delivers a constant flow of fuel to the pipe 17 and this is connected, as described, with the bypass valve. The timing is such, as indicated in Fig. 3, that the forcing pump plunger will be withdrawn and started on its return or forcing 50 stroke before the bypass valve is closed delivering the charge through the inlet valve to the pump chamber so that the pump plunger meets, as it were, the incoming charge and there is a definite and sharp cut-off of the charge of fuel at the moment the 55 chamber is filled. This is a more definite measuring device and is less subject to variation due to frictional resistance, expansion of parts and the expansibility of the fuel than devices which depend on the opening 60 of the bypass valve, or other schemes for determining the cut-off of the flow to the chamber. Further the beginning of the point of discharge to the chamber is definite and immediately controlled by the closing of the bypass valve so that there is a definite 65

starting and definite stopping of the delivery of fuel to the pump chamber and this makes a very accurately measured charge with each stroke of the pump. The governor, it will be seen, controls the moment of closing the 70 bypass valve and consequently controls the moment of the starting of the delivery of fuel to the pump chamber. The time for stopping the flow of fuel to the pump chamber, however, is controlled by the meeting of the incoming fuel—in other words, the filling 75 of the pump chamber rather than the opening of the bypass valve causing resistance to the spray nozzle is sufficient to prevent a discharge from the discharge of the 80 force pump and consequently as soon as the pump chamber is filled and there is a tendency for a forced return movement of the fuel through the inlet valve of the pump this 85 closes this inlet valve and from this point on the trapped fuel in the pump chamber is discharged to the engine cylinder.

While I have shown a gear pump as part of the measuring scheme it will be understood that the device is not limited to this 90 particular type of pump.

It will be noted that the cam 55 has a nose 55^a forcing an ultimate discharge slightly without a circle forming a greater part of the cam. The purpose of this is to 95 permit a slight backward or yielding movement of the plunger to relieve pressure from the spray nozzle and thus prevent leakage from the spray nozzle in the interval between strokes. The cam is also provided with depressions 55^b which permit the intake movement of the plunger under the influence of the spring.

What I claim as new is:—

1. The method of delivering measured 105 quantities of fluids to receiving instruments which consists in delivering fluid to a pulsating pump chamber during the forcing contraction of said chamber and varying the charge by varying the point in the contraction of the chamber at which the chamber is filled.

2. In a charge delivering device, the combination of a pulsating pump chamber; devices delivering charges to the chamber during the discharge contraction of the chamber; and means varying the charge comprising a measuring pump, delivering to the pulsating pump, and devices varying the discharge moment of the measuring pump.

3. In a charge delivering device, the combination of a pulsating pump chamber; devices delivering charges to the chamber during the discharge contraction of the chamber; and means varying the charge comprising a measuring pump delivering to the pulsating pump, and devices varying the discharge moment of the measuring pump, said devices comprising a bypass and variable means controlling the bypass.

4. In a charge delivering apparatus, the combination of a pulsating pump chamber; a loaded inlet valve controlling the flow of fluid to the chamber; a measuring pump discharging through the inlet valve to the pulsating pump chamber; a bypass between the measuring pump and the pulsating pump chamber comprising a loaded valve, the loading of the bypass valve being greater than the loading of the inlet valve; and means actuating the bypass valve to vary the charge. 25
5. In a charge delivering apparatus, the combination of a pulsating pump chamber; a loaded inlet valve controlling the flow of fluid to the chamber; a measuring pump discharging through the inlet valve to the pulsating pump chamber; a bypass between the measuring pump and the pulsating pump chamber comprising a loaded valve, the loading of the bypass valve being greater than the loading of the inlet valve; means controlling the closing of the bypass valve during a forcing contraction of the pulsating pump chamber. 30
6. In a charge delivering apparatus, the combination of a pulsating pump chamber; a loaded inlet valve controlling the flow of fluid to the chamber; a measuring pump discharging through the inlet valve to the pulsating pump chamber; a bypass between the measuring pump and the pulsating pump chamber comprising a loaded valve, the loading of the bypass valve being greater than the loading of the inlet valve; means controlling the closing of the bypass valve during a forcing contraction of the pulsating pump chamber; and mechanism controlling the timing of the closing of the bypass valve to vary the charge. 35

In testimony whereof I have hereunto set my hand.

HAROLD F. SHEPHERD.
